(57) **CLAIM**

The ornamental design for a training bat for use in water, as shown and described.

DESCRIPTION

FIG. 1 is a front perspective view of a training bat for use in water.

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a cross-section view taken along line 7-7 of FIG. 2.

The broken lines shown in the figures represent portions of the training bat for use in water that form no part of the claimed design.

1 Claim, 7 Drawing Sheets
